SIGHTING DEVICE FOR BOWLERS

Louis O. Frey, Pleasant Valley Road, Mendham, N.J.

Filed July 22, 1960, Ser. No. 44,678

6 Claims. (Cl. 33—64)

The present invention generally relates to a device for use by persons engaged in bowling and more particularly is a sighting device for use by bowlers for aiding them in properly directing the ball towards the pins.

In spot bowling, the bowler normally will aim at a particular spot in a spaced relation to the foul line which is usually in an area of the alley which is just previous to the point at which the ball begins to curve towards the pin, pins or pocket which the bowler desires to engage by the ball. By practicing the delivery of the ball and making each delivery substantially identical, a bowler can establish a particular spot in the alley over which the ball should pass in order that the ball will hit or engage a particular pin, pins or pocket.

Accordingly, the primary object of the present invention is to provide a sighting device for bowlers which includes a pair of adjustable points mounted in such a manner that they will be disposed forwardly of the eyes of the bowler so that one pointer may be aligned with the pin or pocket desired to be engaged by the ball and the other pointer may be aligned with a spot on the bowling alley, the pointers being adjustable in relation to each other so that they may be properly adjusted to indicate to the bowler the spot over which the ball is to be rolled in order for the ball to follow a desired path and engage a desired pin, pins or pocket between pins.

Another object of the present invention is to provide a sighting device for bowlers which is quite simple in construction, easy to use, effective for its particular purposes and generally inexpensive to manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view illustrating the sighting device of the present invention in use;

FIGURE 2 is a bottom plan view of the sighting device with portions thereof broken away illustrating the manner of the attachment of the strap to the sighting device; and

FIGURE 3 is a side elevational view of the invention with portions thereof broken away illustrating further structural details thereof.

Referring now specifically to the drawings, the numeral 10 generally designates the sighting device for bowlers of the present invention which is illustrated in use by a bowler 12 with the bowling ball 14 already being released and proceeding down the bowling alley 16 towards the bowling pins 18. The bowler 12 has stopped his forward progress rearwardly of the foul line 20 in the usual manner.

The sighting device 10 includes an elongated supporting arm 22 having an arcuate mounting plate 24 at one end thereof which is adapted to engage the forehead of the bowler 12. The arcuate plate 24 is provided with end slots 26 receiving the ends of a flexible resilient head strap 28 adapted to encircle the head 30 of the bowler 12. The ends of the head strap 28 are secured by any suitable manner such as by stitching, riveting, snap fastener elements or the like whereby the elastic strap 28 is secured to the plate 24 for mounting the arm 22 in forwardly extending relation to the forehead as illustrated in FIGURE 1.

The outer end of the arm 22 is provided with a gen-

2

erally cylindrical enlargement 32 having a vertically disposed frusto-conical or tapered bore 34 extending therethrough for adjustably and rotatably receiving a frusto-conical mounting member or plug 36 having a peripheral flange 38 at the upper end thereof forming a handle or finger grip for the member 36. Depending from the bottom edge of the frusto-conical member 36 is a pair of pins 40 and 42. The pin 40 is elongated and the pin 42 is relatively short and the pins 40 and 42 actually form pointers for alignment with the bowling pins 18 and a spot on the bowling alley 16 in a manner described hereinafter. The construction of the arm and the construction of the plate as well as the member 32 and the member 36 may be of suitable material such as plastic or the like and due to the frusto-conical construction of the member 36 and the bore 34, the pointers 40 and 42 may be adjusted in relation to the line of vision of the bowler and retained in position by merely forcing the frusto-conical member 36 downwardly into the bore 34 thus frictionally locking the pointers in position.

In using the device, it is placed on the head in the manner as illustrated in FIGURE 1 and the bowler 12 lines the short pointer 42 up with the pocket, pin or pins which the bowler wishes to hit. When the sight is lined up in this manner, the bowler moves his eye only and locates the spot directly beneath the long pointer 40 and this is the spot over which he must roll the ball. The spot is usually 10 to 14 feet from the foul line or at a point before the ball starts to break or curve and the points are adjustable to enable the bowler to compensate for the amount of hook or curve which he has on the ball when it is rolled. By using the sighting device several times, the bowler observes where the ball hits, that is, whether to the right or left of the pin thrown at and then readjusts the sight accordingly so that after several throws, the bowler will have a positive means of locating a spot on the bowling alley over which the ball should pass. When the sighting device is properly adjusted, it will locate the spot the player must roll the ball over for any pin, split or group of pins on the alley.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

- 50 1. A sighting device for bowlers comprising an elongated arm, means at one end of said arm for attachment thereof to a bowler's head with the arm extending forwardly therefrom, a pair of spaced vertical pointers mounted on and depending from the outer end of the arm generally forwardly of the eyes whereby a bowler may align one pointer with a bowling pin to be hit by the ball and the other pointer will indicate the spot over which the bowling ball should be rolled, one of said pointers being longer than the other.
- 55 2. A sighting device for bowlers comprising an elongated arm, means at one end of said arm for attachment thereof to a bowler's head with the arm extending forwardly therefrom, a pair of spaced vertical pointers mounted on and depending from the outer end of the arm generally forwardly of the eyes whereby a bowler may align one pointer with a bowling pin to be hit by the ball and the other pointer will indicate the spot over which the bowling ball should be rolled, said means for attachment to a bowler's head including an arcuate plate adapted to engage the forehead of a bowler and a resilient strap attached at its ends to said plate for encircling the head and retaining the plate and arm in position on
- 60
- 65
- 70

the head with the arm generally extending forwardly above the eyes, said arm being provided with a vertically disposed tapered bore in the outer end thereof, and a frusto-conical mounting member adjustably mounted in said bore, said pointers depending from the lower end of said mounting member.

3. The combination of claim 2 wherein one of said pointers is shorter than the other of said pointers, the short pointer being adapted to be aligned with the desired pin, pins or pocket to be engaged by the ball and the other pointer being adapted to indicate the spot on the alley over which the ball should be rolled.

4. The combination of claim 3 wherein the frusto-conical mounting member and the bore are provided with complementary tapering surfaces for frictional engagement thereof when downward pressure is exerted on the mounting member, said mounting member including a peripheral flange at the upper end thereof for providing a finger piece for lifting and rotating the mounting member for adjusting the orientation of the pointers so that the point indicated on the alley may be varied for the individual bowler depending upon the characteristics of

the path of the ball when rolled by the particular bowler thereby enabling the spot on the alley to be varied.

5. A sighting device comprising an elongated arm, pointer means attached to said arm, and means on said arm remote from the pointer means for attachment of the device to the head of a bowler, said pointer means including a pair of pointers mounted generally forwardly of the eyes, one of said pointers being shorter than the other.

6. The structure as defined in claim 5 wherein frictional lock means interconnects the pointers and the arm for locking the pointers in adjusted position.
